[57] CLAIM

The ornamental design for a vehicle attached article carrier for lumber or the like, as shown and described.

DESCRIPTION

FIG. 1 is a perspective view of a vehicle attached carrier for lumber, or the like, showing my new design positioned along with a second carrier mounted upon the side of a vehicle, with the carriers supporting elongated articles, and with the second carrier, vehicle portion and boards shown in broken lines for illustrative purposes only, and forming no part of the claimed design;

FIG. 2 is a right side elevational view thereof;
FIGS. 3 and 4 are respectively top and bottom plan views thereof; and

FIGS. 5 and 6 being are respectively front and rear elevational view thereof.

Fig 1.

Fig 2.

Fig 1 2.

Fig 1 3.

Fig 2 1.
